UNITED STATES PATENT OFFICE.

MORRIS J. MEYER AND OSCAR W. SCHIMDT, OF ST. LOUIS, MISSOURI.

DESIGN FOR A TOBACCO-PIPE BOWL.

SPECIFICATION forming part of Design No. 29,664, dated November 15, 1898.

Application filed August 29, 1898. Serial No. 689,814. Term of patent 14 years.

To all whom it may concern:

Be it known that we, MORRIS J. MEYER and OSCAR W. SCHIMDT, of the city of St. Louis, State of Missouri, have invented a new and original Design for Tobacco-Pipe Bowls, of which the following is a full, clear, and exact description, reference being had to the accompanying drawing, forming a part hereof.

The figure is a perspective view of a tobacco-pipe bowl embodying our design.

As shown in the drawing, the leading or material feature of our design consists of a hollow cylinder 1, the same tapering slightly toward the lower end, and around said lower end is arranged a continuous bead 2, and there being a short body 3, having a curved face 4 extended downwardly from said bead.

We claim—

The design for a tobacco-pipe bowl, substantially as herein shown and described.

In testimony whereof we affix our signatures in presence of two witnesses.

MORRIS J. MEYER.
OSCAR W. SCHIMDT.
